UNITED STATES PATENT OFFICE.

CHARLES F. GILES, OF LOUISVILLE, KENTUCKY, ASSIGNOR, BY MESNE ASSIGNMENTS,
TO WALTER P. MURPHY, OF CHICAGO, ILLINOIS.

METAL CAR END.

1,351,566.

Specification of Letters Patent. Patented Aug. 31, 1920.

Application filed May 8, 1916. Serial No. 96,071.

To all whom it may concern:

Be it known that I, CHARLES F. GILES, a citizen of the United States, residing at Louisville, in the county of Jefferson and State of Kentucky, have invented certain new and useful Improvements in Metal Car Ends, of which the following is a specification.

This invention relates to that class of car ends designed primarily for freight car building or repair and which comprise metal sheets corrugated to stiffen them and better adapt them to withstand forces which they must encounter in use.

One object of the present invention is to so dispose the main area of stiffening corrugations so as to insure superior strengthening effect, and in addition thereto, to improve the appearance of the structure; to 20 which end, the corrugations covering the main area of the sheet metal end, extend horizontally and nearly from side to side of the car.

Another object is to increase the resistance 25 of the sheet or sheets to buckling; to which end, another feature consists in providing vertical corrugations in position to extend across the ends of the horizontal corrugations and to lie adjacent to the corner posts 30 of the car, when the sheet is in position.

Another object is to adapt the sheet to absorb as far as practicable, strains and vibrations exerted in the plane of the sheet and in the general direction extending from 35 side to side of the car, so as to reduce the tendency to loosen the marginal fastenings of the sheet as the framing of the car yields to swaying motion in travel, which object is also attained to a beneficial degree by the

40 vertical corrugations lying beyond the ends of the horizontal corrugations and near the corner posts, but is insured to a still greater degree by having vertical corrugations with which the horizontal corrugations merge at 45 the ends of the latter, so that the aforesaid strains transversely to the car and in the plane of the sheet, which may be transmitted by the longitudinally rigid horizontal corrugations, will be absorbed largely by the 50 merging vertical corrugations. A still further object is to provide a structure which will most effectively combine both the above-named features, namely, security against buckling and for the proper transmission 55 of lateral strains, to which end, a further

feature of the invention consists in combining with the horizontal corrugations, a plurality of vertical corrugations near each corner post, one of which preferably merges with the ends of the horizontal corrugations. 60

A still further object is to develop in sections, sheets adapted to be combined in covering the necessary area of a car end, and to construct these sectional sheets so that when desired, sheets may be combined to develop a continuous car-end area in which the several structural characteristics of the invention exist without interruption, to which end a further feature consists in constructing sections of the end covering with two sets of 70 corrugations, one set lying perpendicular to the other, extending to overlapping margins of the sheet sections, and with corresponding corrugations on the respective sections nesting or overlying one another, so that 75 there is no interruption in the characteristic structural features throughout the sheet, and the sections interlock in the direction of the plane of the sheet. It is to be understood, however, that it is a matter of election 80 whether this last-named feature of the invention be embodied, or whether the sheet sections are provided with flat attaching margins where they meet or overlap.

The invention will be more fully understood from two illustrative embodiments disclosed in the accompanying drawings, in which—

Figure 1 is an end view of a conventional type of freight car;

Fig. 2 is a section on the line 2[—]2[—] of Figs. 1 and 4;

Fig. 3 is a section on the line 3[—]3[—] of Fig. 1;

Fig. 4 is a view similar to Fig. 1, showing 95 the use of additional vertical corrugations near the corner posts;

Fig. 5 is a section on the line 5[—]5[—] of the corrugated sheet employed in Fig. 4, the car framing being omitted,

Figs. 6 and 7 are two half-elevations of a car end showing modifications of the forms shown in Figs. 1 and 4, respectively, according to which modifications, the horizontal and vertical corrugations of the upper and lower sheet sections are continued to the overlapping margins of the sections and, Figs. 8 and 9 are sectional views taken on lines 8—8 and 9—9 of Fig. 6.

1 represents the end plate, 2 the corner 110

posts, 3 the end rails, 4 the end sill, 5 the lining, and 6 the end fascia board of a conventional type of freight car, which parts are usually made of wood, but may, for the purposes of the present invention, be constructed of any other suitable material.

In place of the outer sheathing of the car body at the ends at least, the present invention supplies for each end, a sheet metal facing, preferably consisting of two plates 7, 8, (Figs. 1, 2 and 3), or 7^a, 8^a, (Figs. 4 and 5), or 7^b, 8^b, (Figs. 6 and 7), placed in position with the top margin 9 of the upper plate secured beneath the fascia board 6, with the meeting edges of the plates overlapped as shown at 10 (Figs. 1 to 5) or 10^b (Figs. 6 and 7), and with the lower margin 11 depending in the form of a drip apron over the end sill 4; while the vertical side marginal portions of the sheets are shaped as at 12 and 13 around the corner posts 2, to which they may be suitably attached and additionally secured by the corner straps 14. But while these conditions are preferably embodied in carrying out my invention, they may be changed without departing from the spirit thereof in its broader aspects. The continuing of the corrugations to the meeting margins of the sheet sections provides an interlock in the direction of the plane of the sheet and is an important feature of the present invention. It is, however, not to be understood as a limitation in the scope of that portion of the invention which relates in the horizontal corrugations combined with vertical marginal corrugations.

According to all the forms, the sheets are provided throughout the main portion of their area with horizontal corrugations 15, extending nearly from side to side of the car, and with intervening corrugations 16, preferably, though not necessarily, of curved or sine-wave form and extending oppositely from the intermediate or neutral line; but these corrugations may be spaced apart vertically with plane surfaces in between them, or they may be pressed at vertically spaced intervals in one direction only from the original plane of the sheet. The outwardly presented corrugations are preferably made to receive the end rails 3, so that those presented inwardly, or the inner surface of the sheet, can rest in abutment against the lining 5.

At the ends of the horizontal corrugations 15, 16, and adjacent to the corner posts of the car frame, are vertical corrugations 17 in position to prevent the sheet buckling or rolling upon an axis parallel to the horizontal corrugations, and these vertical corrugations, if one set only is used, are preferably merged with the ends of the horizontal corrugations as shown at 18 in Figs. 1 and 3. They may, however, be spaced from the ends of the horizontal corrugations without sacri-

ficing all of the benefits of this feature of the invention.

According to Figs. 4, 5 and 7, additional vertical corrugations 19 may be employed near the corner posts, and these are preferably spaced from the corrugations 17 by an intervening corrugation 20. They may, however, be spaced a greater distance by flat portions of the sheet surface.

With a sheet steel end for freight cars 75 constructed in accordance with Figs. 1 and 3 or Figs. 4 and 5, or Fig. 6, or Fig. 7, the structure is rendered strong and rigid against internal or external thrusts longitudinally of the car, as for instance those 80 resulting from shifting cargo; strains transmitted athwart the car end and which resolve themselves largely into diagonal stresses will be largely absorbed by the relation of horizontal corrugations covering the intermediate area and vertical corrugations near 85 the corner posts; and the sheets are left with smooth margins, which render them very convenient for attachment to the existing 90 frame members of conventional freight 95 cars; and when the corrugations are continued to the overlapping margins of sheet sections as shown in Figs. 6, 7, 8 and 9, and these overlapping margins have their corrugations nesting or overlapping, as 100 shown, and suitably secured to the framing, additional rigidity is lent to the structure and the main purposes of the invention are realized to even a greater degree.

100

I claim:-

1. A metal facing member for railway cars comprising a metal sheet constructed for attachment to vertical and horizontal portions of the car body, with its main area shaped with horizontal corrugations extending nearly to the vertical margins of the sheet, and with vertical corrugations near said vertical margins lying transversely across the ends of the horizontal corrugations; there being a plurality of said vertical corrugations at each end of the horizontal corrugations; one of the vertical corrugations being merged with ends of the horizontal corrugations, and the adjacent vertical corrugation being spaced from said merged corrugation.

105

2. A metal facing member for railway cars comprising a metal sheet constructed for attachment to vertical and horizontal portions of the car body, with its main area shaped with horizontal corrugations extending nearly to the vertical margins of the sheet, and with vertical corrugations near said vertical margins lying transversely across the ends of the horizontal corrugations; there being a plurality of said vertical corrugations at each end of the horizontal corrugations; one of the vertical corrugations being merged with ends of the horizontal corrugations, and the adjacent vertical corrugation being spaced from said merged corrugation.

110

115

120

125

130

vertical corrugation being spaced from said merged corrugation by an intervening corrugation of the metal.

3. In combination with a freight car having vertical corner posts, a sheet metal end member formed at its vertical margins for attachment to said vertical corner posts of the car frame and having the main portion of its area lying therebetween formed with 10 horizontal corrugations extending nearly to the corner-post attaching-portions of the sheet, and with a plurality of vertical corrugations formed in the sheet between each corner-post attaching-portion of the sheet 15 and the adjacent ends of the horizontal corrugations; one of the vertical corrugations being merged with the adjacent ends of the horizontal corrugations.

4. A sheet metal end structure for a railway car, comprising a metal sheet formed with a plurality of parallel corrugations which merge one into another and formed with a rigidifying corrugation extending transversely to the first mentioned corrugations, and merging into their extremities. 20

5. A sheet metal end structure for a railway car, comprising a metal sheet formed with a plurality of horizontally disposed, parallel corrugations which merge one into 25 another and formed with rigidifying corrugations which merge into the extremities of said horizontal corrugations.

6. A sheet metal end structure for a railway car, comprising a metal sheet formed 30 with a rigidifying corrugation extending substantially across the sheet and formed with a plurality of parallel corrugations which merge one into another throughout their length and which merge at their extremities adjacent one edge of the sheet into one side of said first mentioned corrugation. 35

7. A sheet metal end structure for a railway car, comprising a metal sheet having its edges bent to overlap the corner post of the 40 car, a rigidifying corrugation extending substantially across the sheet, a plurality of parallel corrugations which extend transversely of said first mentioned corrugation and merge at their extremities into one side 45 only of said first mentioned corrugation.

8. A sheet metal end structure for a railway car comprising a metal sheet formed with inwardly pressed, vertically extending corrugations adjacent opposite edges of the 50 sheet, and the edges bent back to provide

end post receiving grooves between said corrugations and said edges, corrugations spaced inwardly of the first mentioned corrugations, and transverse corrugations extending across the space between said second mentioned corrugations and merging at their extremities into the sides of the said second mentioned corrugations. 60

9. A sheet metal end structure for a railway car comprising a sheet having a plurality of adjacent corrugations extending uninterruptedly across the sheet, and a corrugation extending along each of the edges of the sheet transverse to the first mentioned corrugations into which the extremities of 70 the first mentioned corrugations merge.

10. An end sheet for railway cars having parallel corrugations providing continuous 75 uninterrupted rigidifying beams extending substantially across the sheet, and rigidifying corrugations adjacent the margins of said sheet and merging into the extremities of all of said first mentioned corrugations.

11. An end sheet for railway cars having parallel corrugations providing continuous 80 uninterrupted rigidifying beams extending substantially across the sheet, and inwardly pressed rigidifying corrugations adjacent the margins of said sheet and merging into the extremities of all of said first mentioned 85 corrugations.

12. A sheet metal end structure for a railway car, comprising a sheet having a plurality of corrugations extending uninterruptedly across the sheet and merging one 90 into the other throughout their length, and a transversely disposed corrugation adjacent each of the margins of the sheet into which the extremities of said first mentioned corrugations merge. 95

13. In combination with the corner posts of a railway car of a sheet metal end structure for the car comprising a sheet having a plurality of adjacent horizontally disposed corrugations extending across the car substantially from corner post to corner post and a corrugation on each of the edges of the sheet transverse to the first mentioned corrugations into which the extremities of the first mentioned corrugations merge. 100 105

The foregoing specification signed at Louisville, Kentucky, this 17th day of April, 1916.

CHARLES F. GILES.
